Primary Examiner — Philip S Hyder*Assistant Examiner* — Cary M Robinson(74) Attorney, Agent, or Firm — McAndrews Held & Malloy, Ltd.(57) CLAIM

The ornamental design for a display screen or portion thereof with an icon, as shown and described.

DESCRIPTION

FIG. 1 is a front view of a display screen or portion thereof with an icon showing my new design; and, FIG. 2 is an enlarged view of the icon of FIG. 1. The broken lines in FIG. 1 illustrate a display screen or portion thereof and form no part of the claimed design.
